ARM SWIM FLOAT

Konstantin B. Lukas, 300 SW. 18th Ave.,
Fort Lauderdale, Fla.

Filed Feb. 8, 1965, Ser. No. 83,715

Term of patent 14 years

(Cl. D71—1)

FIG. 2

FIGURE 1 is a perspective view of an arm swim float showing my new design; the side opposite FIGURE 1 is the same except for the omission of the valves;

FIGURE 2 is a side elevational view of the arm swim float.

I claim:

The ornamental design for an arm swim float, as shown and described.
